CLAIM

The ornamental design for a kinetic sculpture, as shown and described.

DESCRIPTION

FIG. 1 is a perspective view of this inventive kinetic sculpture.

FIG. 2 is a front view of the kinetic sculpture shown in FIG. 1. The right side view, the left side view and the rear view are identical to the front view.

FIG. 3 is a top view of the kinetic sculpture shown in FIGS. 1 and 2.

FIG. 4 is a bottom view of the kinetic sculpture shown in FIGS. 1-3.

FIG. 5 is a plan view of the kinetic sculpture shown in FIGS. 1-4 taken on view line 5—5 of FIG. 2.

FIG. 6 is a plan view of the kinetic sculpture shown in FIGS. 1-5 taken on view line 6—6 of FIG. 2.

FIG. 7 is a cross-sectional view of the kinetic sculpture shown in FIGS. 1-6 taken on line 7—7 of FIG. 5; and,

FIG. 8 is a cross-sectional view of the kinetic sculpture shown in FIGS. 1-7 taken on line 8—8 of FIG. 6.

The broken lines are included for the purpose of illustrating portions of the kinetic sculpture that form no part of the claimed design; and are shown partially broken away in FIG. 1 for ease of illustration.
